PLASTIC BOBBY PIN

Samuel Berman and Vincent J. Macaluso,
Bayonne, N. J.

Application April 29, 1944, Serial No. 533,375

6 Claims. (Cl. 132—50)

This invention relates to plastic bobby pins.

One object of the invention is to provide an improved plastic bobby pin adapted to maintain its shape and resilience to a high degree.

It is well known that plastic materials have relatively little resilience and tend to return to initial shape rather slowly, providing that the elastic limit has not been exceeded. But since the elastic limit is low, a plastic bobby pin would remain permanently distorted if subjected to the deformations that are normal in the use of a spring steel bobby pin. This applies especially to plastics that are used in the inexpensive process of injection molding. For these reasons it appeared at first that the provision of a plastic bobby pin was a difficult if not an impossible problem.

It is therefore an object of the invention to provide a plastic bobby pin having improved means to avoid the difficulties mentioned and to provide an inexpensive article adapted to be made up in different attractive colors to suit the hair of the wearer.

More particularly, it is an object of the invention to provide a bobby pin consisting in the main of plastic material with improved metallic spring means connected thereto so as to supply a major portion of the required resilient range of deformation, thus assuring that any deformation in the plastic material shall be well within its elastic limit, and the metallic portion being so small as to be relatively inconspicuous. In such a bobby pin the plastic material may furnish a body which is in one piece or which may be split so that the legs are separated and interconnected only by the metallic spring. The latter may be connected to the legs of the bobby pin by embedment therein or by releasable or permanent means.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is an enlarged side view of a bobby pin embodying the invention.

Fig. 2 is a top plan view thereof.

Fig. 3 is an end view thereof.

Figs. 4, 5, and 6 are enlarged sectional views taken respectively on lines 4—4, 5—5 and 6—6 of Fig. 1.

Fig. 7 is a further enlarged fragmentary side view of a modified bobby pin.

Fig. 8 is a sectional view on line 8—8 of Fig. 7.

Fig. 9 is a fragmentary side view of another modification.

Fig. 10 is a view in end elevation of the spring thereof.

Fig. 11 is a view in elevation of the closed, opposite end of the spring.

Fig. 12 is a fragmentary side view of still another modification.

Fig. 13 is a view in end elevation thereof.

The advantages of the invention as here outlined are best realized when all of its features and instrumentalities are combined but, useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing 15 denotes a bobby pin embodying the invention. The same may include a molded hair clasping member 30 which comprises opposed legs 16, 17 of which preferably at least one is formed with crimps. These legs may be interconnected by an integral loop portion 18 although this may be split as shown in Fig. 12, or may even be wholly eliminated except as it may be used to assist in connecting a metallic spring loop element 19 to the legs 16 and 17. This element 19 may externally embrace the loop portion 18, although it may also be embedded therein as in Fig. 7 or lie internally

40 thereof as in Fig. 9. Securing the extensions or arms of the loop element to the legs 16, 17 or at least to the arms of the loop portion 18 is an improved means located at 20 and at two points designated as 21, 22. At each of these locations

45 is provided a seat 23 formed by striking a depression in the spring 19 and providing a corresponding depression or cavity to receive the same. Thus there are three identical means 20, 21 and 22 each constituting a male and female intercon-

50 necting means, of which the means 20 operates at an angle to those at 21, 22 and prevents lateral shifting of the loop element 19. The difference is more readily apparent by considering that the means 20 is assembled or engaged by a 55 movement of the expanded loop spring leftward

in Fig. 1 axially of the bobby pin, after which the loop element is merely released for interengagement at 21, 22 under the resilient pressure exerted by the loop element 19 against the legs 16, 17. Thus a very simple structure permits a very rapid assembling by a snap action locking engagement.

It is intended that the resilience required for the ample opening or deformation of the bobby pin to receive a tuft of hair shall be supplied mainly by the loop element 19; of course some deflection of the legs 16, 17 will occur, but this is secondary and in any case should be well within the elastic limit of the plastic material in order that the bobby pin shall always be adapted to return to initial position. Accordingly, the legs 16, 17 may be made with sufficient body for the required stiffness. For example, the leg 16 may have a longitudinal central integral rib 24 at least within the depressions thereof, although it may also extend over the humps of the crimped leg as in Figs. 7 and 9. Also the leg 17 may be suitably thickened, but greater stiffening is needed for the leg 16 because of its effective greater length due to its crimped shape. Further, the straight sides of the loop portion 18 may be thickened to avoid undue bending and strain thereof. It is thus seen that the bobby pin 15 assures a relatively uniform clamping action on the hair, instead of as heretofore, since the main resilient force is concentrated in the loop element 19. Of course the loop portion 18 may be so thin as not to materially restrain or affect the action of the element 19.

In Figs. 7 and 8 is shown a modified bobby pin 25 according to the invention. The same may comprise a member having legs 26, 27 of plastic material, in which is embedded at least part of a metallic spring loop 28. Preferably said member also includes a loop portion 29 joining the legs and encasing the spring loop. Preferably, one side of the loop is substantially longer than the other as shown at 28a and extending for substantially the entire length of the leg 27, the material of which may be quite thin so as to readily deform under control of the spring metal. To the contrary the leg 26 is intended to be almost rigid, having a rib 30 like that at 24 but also continuing over the external points of the crimps as at 31. In fact this rib may continue at 32 up to the curved portion of the loop. It has been found to be a material improvement to prevent outward lateral deformation of the crimped leg, as it tends to reduce the depth of the crimps and hence the holding power of the bobby pin on the hair. It is therefore better that any resilience in the legs be concentrated in the straight leg. In this respect the device 25 may be considered to possess an advantage over that at 15 because the loop need be relied upon for a lesser degree of resilience; or, differently stated, the resilience may be spread over a greater length of the bobby pin to include the leg 27 as well as the loop. The thickness of the plastic material may be varied so that more or less of the resilience may occur per unit of lineal length of the loop as compared with that in the leg 27, per unit of its length. The spring 28 suitably crimped or straight may be extended through the leg 26 or rib thereof.

The bobby pin 25 may be made by injection molding as by suitably placing the loop element in the die and then molding the plastic to complete the article.

In Figs. 9 to 11 is shown another modified bobby pin having legs 34, 35 of plastic material

interconnected by a plastic loop portion 36 within which is disposed a metallic loop spring 37 secured at points 38, 39, 40. The securing at 38 may be like that at 20, but the securing at 39, 40 may be afforded by striking prongs 41 and inserting them through holes in the legs, after which the projecting ends of the prongs are bent or headed over externally of the legs so that the spring is operative to pull the legs together for clamping on a tuft of hair. The device 33 thus illustrates the reverse mounting of the spring as compared with the device 15, but its ribbed formation for the crimped leg may be as in the device 25.

In Figs. 12 and 13 is shown a modified bobby pin 42 which may be like that at 15 except that the loop portion 43 between the legs 44, 45 is split at 46. In other words, the legs 44, 45 may be separately molded and then interconnected by the metallic spring loop 47 at points 48, 49, 50, 51, so that there are two points of connection for each leg to prevent any lateral or angular shifting, the engaging means at the points mentioned being like those in the device 15. If desired the legs may pivot or bear on each other at the split 46. Thus excessive strain on the plastic at the loop is avoided, and if desired, the plastic may also be omitted at the curve of the loop element 48. A stiffening rib 52 may be provided.

We claim:

1. A device including a bobby pin having a member comprising opposed legs of plastic material, a metallic loop spring element having a curve in its loop portion of more than 180 degrees and having longitudinal portions extending partway along the legs and resiliently bearing thereon a first means for interconnecting the element and said member, said means comprising a projection and an opening to receive the same so that said means is operative at one end of the member by movement of the element in a direction toward the other end of the member to prevent lateral shifting of the element relative to the member, and a second means remote from the first means for individually interconnecting the legs with said portions, including a projection and an opening to receive the same, at each leg, such that the second means is operative in a direction transverse to the legs and in the plane of resilience of the loops, the second means holding the first means in interconnected position, the second means being maintained in interconnected position by the pressure of said longitudinal portions on the legs.

2. A device including a member having legs consisting of plastic material, one of the legs being straight and the other crimped, and provided with a reinforcing longitudinal wholly external rib transverse to the crimps, the crimps on the internal side of the leg being independent of said rib.

3. A device including a bobby pin having legs of plastic material having curved portions forming a closed end for the pin, an external metallic U-shaped spring receiving the closed end of the pin and extending at least partly along the legs, a first means interconnecting the spring with the curved portions of the legs to prevent lateral movement between the pin and spring, and a second means interconnecting the spring with the legs remotely from said curved portions to prevent relative movement between the spring and pin, the first and second means including releasable male and female means maintained

engaged by the pressure of the spring urging the legs together.

4. A device including a bobby pin having legs of plastic material having curved portions forming a closed end for the pin, a metallic generally U-shaped, spring externally embracing the portion of the pin adjacent to the closed end thereof and urging the legs toward each other, and male and female releasably interengaging means between the pin and spring, said means being maintained engaged by the resilience of the spring urging the legs toward each other.

5. A device according to claim 3, wherein the curved portions are separate of each other and are maintained in contact with each other by the spring, the curved portions having pivotal engagement with each other in expanding the pin.

6. A device according to claim 4, wherein the curved portions are separate of each other for pivotally bearing on each other, the spring operatively maintaining the curved portions in expansion and contraction of the pin.
